UNITED STATES PATENT OFFICE.

CHARLES ALFRED MARCHAL, OF PARIS, FRANCE, ASSIGNOR TO SOCIETE ANONYME DES USINES A. E. DECOUFFLE, OF PARIS, FRANCE.

CIGARETTE-MACHINE.

No. 903,101.

Specification of Letters Patent.

Patented Nov. 3, 1908.

Application filed October 21, 1907. Serial No. 398,420.

To all whom it may concern:

Be it known that I, CHARLES ALFRED MARCHAL, a citizen of the Republic of France, residing in Paris, France, have invented certain new and useful Improvements in Cigarette-Machines, of which the following is a specification.

The invention aims to provide a machine for the rapid manufacture of cigarettes closed at one end.

The accompanying drawings illustrate an embodiment of the invention.

Figure 1 is a side elevation, Fig. 2 a plan, and Fig. 3 an end elevation of the complete machine with parts broken away and small details omitted for the sake of clearness; Fig. 4 is an end view of the mechanism for closing the end of the cigarette; Figs. 5 and 6 are respectively a side and an end elevation 20 of the mechanism for inserting the tobacco; Figs. 7 and 8 are respectively a side and an end elevation of the tube forming mechanisms; Figs. 9 and 10 are respectively a side and end elevation of the mechanism for conveying tubes and inserting the tobacco.

Referring to the embodiment of the invention illustrated, the paper is fed in a continuous strip over a pin about which its edges are brought together so as to form a tube. The continuous tube of paper thus formed is fed to an apparatus which closes its end, after which a sufficient length to form the cigarette is cut off, and the tube with one end closed is conveyed to another point where the tobacco is inserted, after which the finished cigarette is carried off to be boxed.

The paper A passes over the round pin B (Figs. 1 and 7) about which its edges are brought together, and is conveyed forward by the yielding roller C which rotates continuously. The edges of the paper pass under pressure between the roller C and the smaller roller D located within the rod B, which clamps together the edges of the tube. The tube feeds forward continuously by the rotation of the roller C, and passes into a barrel or mouth E which carries the mechanism for closing the end of the tube. When the tube passes far enough out of the end of the barrel E for effecting the closure (about $6\frac{1}{2}$ millimeters) its edges are pressed inward by the notched plate F (Figs. 4 and 8) so as to close the end. The plate F is carried

on the barrel, the opposite end of the sleeve carrying the pinion H rotating at a rapid rate of speed about the barrel, and consequently carrying the plate F around at a rapid rate. The plate F is carried upon a pin I passing through the ring G and having at its opposite end a crank a which has a pin bearing on the cam b. The cam b rotates with a pinion c, the two constituting a sleeve upon the sleeve which carries the members G and H. The pinions H and c are rotated simultaneously by gears F³ and G³ and at slightly different speeds, so that after a determined number of revolutions of both pinions the cam b will have made a complete revolution relatively to the crank a, and will have caused a movement of the plate F from its outermost to its innermost position and back, so as to close the end of the tube and return to its original position. The cam is so proportioned that the notched part of the plate F passes slightly beyond the center of the tube and is then retracted to permit the tube to pass forward.

The continued forward movement of the tube causes its forward end to enter one of the notches or pockets (the uppermost one) of a carrier consisting of a pair of plates J J' (Figs. 9 and 10), the two plates being mounted on an intermittently rotating shaft K. As the forward end of the tube enters the carrier, the tube is cut off at a suitable length by the scissors L (Fig. 8). The opening and closing of the scissors is effected by the lever M furnished with two small rollers N N' acting on the arms P P' of the scissors, and furnished with a roller O bearing against a horizontal extension 2 (Fig. 1) of an arm R which is pivoted at S and is swung inward by means of a cam U engaging a roller T on the arm R. Normally the scissors are held open by a spring P². The scissors and lever M are mounted on a support V which is carried on the forward end of a slide X reciprocated by means of the lever Z which is actuated by the cam Y, and which is connected to the slide X by the connecting rod A' (Figs. 7 and 8). The rear end of the slide X runs in a groove in the fixed guide block S².

In order to cut the tube, the cam Y advances the slide X at the same speed as the tube is moving, and the lever M is swung to close the two blades of the scissors. When the tube is cut, the blades of the scissors remain closed and the slide X, continuing its

course, pushes the cut tube into the pocket of the carrier $J J'$ in the position shown at B' , Figs. 9 and 10, (the forward end of the tube having been already engaged with the pocket at the moment of cutting). The scissors then open and the slide X moves backward ready to cut and push another tube.

In order to hold up the tube of paper as it passes through the notch in the first plate J in which position its rear end is cut off and pushed by the scissors L , a small concave supporting piece C' guides it to the corresponding notch of the second plate J' , this guide being placed between the two plates $J J'$ so as not to hinder the movement of the tube when the carrier rotates a step.

The tube of paper being thus introduced into the carrier J , the carrier is immediately revolved a step corresponding in length to the space between the successive notches, so as to present an empty notch to the next arriving tube. The notches of the carrier J are thus furnished successively with paper tubes. In order to hold them in the carrier, a guide D' passes over a portion of the circumference of the plates $J J'$. The guide D' is supported by a bracket 3 in the rear of the carrier, as shown in Figs. 2 and 10.

As the tubes arrive at the lower part of the carrier $J J'$, that is to say at the point E' , they escape the guide D' and fall into one of the notches of the larger carrier F' whose upper portion passes between the two plates $J J'$, and which takes the tubes from the first carrier. The second carrier F' is twice as large as the first carrier $J J'$, and has twice as many notches.

The successive movements of the carriers $J J'$ and F' is effected as follows:—On the shaft G' is fixed a ratchet wheel H' carrying a number of teeth equal to the number of notches of the carrier F' . A pawl I' (Figs. 3, 9 and 10) connected to a lever d controlled by a cam K' , acts on the ratchet wheel, and at each turn of the controlling shaft advances the wheel H' one tooth. A toothed wheel L' fixed on the shaft G' engages with a pinion M' on the shaft K , the sizes of the pinions being proportioned to the numbers of notches in the carriers $J J'$ and F' respectively. Consequently at each step of the carrier F' there is a corresponding movement of the carrier $J J'$, so as to supply the empty tubes to the carrier F' . The fixity of the carriers between the successive steps is obtained by a plate e (Figs. 9 and 10) furnished with a number of teeth equal to the number of notches of the carrier F' . A roller s' mounted on a rod P' and guided in a support R' , is forced up into the spaces S' between the teeth of the plate e under the pressure of a spring T' so as to hold the plate and the carriers in position during the rearward movement of the pawl.

The tubes are held in the carrier F' by means of a guide U' depending from a hanger 4 fastened to a forward bracket 5 which carries also the upright bracket 6 of the concave support C' . The guide U' is curved about the circumference of the carrier. Upon arriving at the point V' the tubes are successively pushed by the pusher X' until their open ends pass over the fixed funnel Y' of the tobacco mold Z' , and thereupon the rod 75 of tobacco contained in the mold is pushed into the paper tube by means of the rod A^2 (Figs. 1, 2, 5, and 6). The cigarette is then pushed off the funnel Y' by the same rod A^2 , and the carrier F' continuing its step by step 80 rotation, brings the successive tubes to the point V' where they are filled with tobacco.

When the cigarettes arrive at B^2 the guide U' terminates and they escape from the carrier F' and fall on to an endless belt E^2 , at the 85 outer end of which they are collected by the operator and put in boxes.

The movements of the pusher X' and of the rod A^2 are shown best in Figs. 1, 5, 6, 9 and 10. Two cams F^2 and G^2 keyed on the same shaft C^2 , communicate the necessary movements to levers H^2 and I^2 . The lever H^2 acts directly on the rod J^2 , the head of the lever being arranged in a mortise in the rod, and the rod J^2 carries at its end the pusher 95 X' . The lever I^2 is connected to an intermediate point of the rod A^2 by a link connection composed of a fork K^2 and a pair of links L^2 and L^3 pivoted to a collar M^2 . The rod J^2 is carried in tube 7 supported upon the bed of 100 the machine and braced by a connecting member 8 to the bearing 9 of the outer end of the shaft G' (see Figs. 1, 2 and 3). The rod A^2 is supported at its forward end in the tobacco mold Z' and at its rear end in a tube 105 supported on the machine bed.

The tubes of paper in the second carrier are adjusted laterally by the guide N^2 fastened on the guide U' so as to insure that when they come to the point V' they will be 110 slightly beyond the end of the funnel Y' , as shown in Fig. 9. Figs. 1 and 2 show the tube pushed on the funnel Y' and ready to be filled with tobacco.

To return to the tube forming and closing 115 mechanism, it will be understood that since the paper is advancing continuously the mechanism supported by the barrel E for closing the end of the tube must move with the tube while the closure is being effected. 120 For this purpose the barrel E is mounted by means of a bracket 11 on a support P^2 fixed on a slide R^2 guided in the support S^2 . A lever T^2 hinged at U^2 and actuated by the cam V^2 acts on the slide R^2 through a roller 125 X^2 (Fig. 8). When the tube of paper is passed beyond the end of the barrel E the distance necessary for its closure, the cam V^2 causes the slide R^2 to advance at the same speed as the paper, and with it the support 130

P^2 and the barrel E . When the tube closing plate F is withdrawn after having closed the end of the tube, the cam causes the return of the slide backward for the following tube. 5 The slide is shown in an advanced position in Figs. 1 and 2 and in a retracted position in Fig. 7.

The movement of the members carried on the barrel E is obtained by the following 10 mechanism:—A toothed wheel Y^2 keyed on the shaft Z^2 operates an intermediate gear A^3 B^3 , shown in dotted lines in Fig. 3, and the gear A^3 in turn operates the pinion C^3 fixed on the shaft D^3 . In the machine shown the 15 ratio of the gearing is such as to turn the shaft D^3 five revolutions for each revolution of the shaft Z^2 . The shaft transmitting the continuous rotary movement to the gears on the barrel E is in two parts, a fixed part D^3 on 20 which the pinion C^3 is carried, and a movable part E^3 carrying the pinions F^3 and G^3 and reciprocating with the support P^2 . The shaft D^3 is furnished at its end with a key H^3 which slides in a groove in a sleeve I^3 pinned on the 25 end of the shaft E^3 . During the movement of the slide R^2 and of the shaft E^3 the grooved sleeve I^3 slides over the key H^3 , so that the rotation of the shaft E^3 continues. Furthermore in order to obtain a good close- 30 sure and to retain the cylindrical form of the tube up to the point at which the closure is made, a supporting surface 12 is provided against which the plate F presses the paper. That is to say the tube is filled nearly to its end 35 by a small cylinder during the time that the closure is being made. For this purpose the rod B (Figs. 1, 2, and 7) is in two parts. The central part is fixed and carries the small yielding roller D . This middle portion of the 40 rod B is extended at opposite ends to form two smaller fixed rods J^3 and K^3 which serve as guides for the movable part. The movable part is composed of two small tubes M^3 N^3 , connected to each other by a small rod 13 located in a groove in the fixed part, and sliding upon the rods J^3 and K^3 . This movable part M^3 N^3 moves with the mechanism car-

ried by the barrel E . The connection is effected by means of a finger O^3 located in a groove in the tube N^3 . The finger O^3 is connected to a hub P^3 angularly adjustable on a support 14 fixed to the slide R^2 . Since the end M^3 of the movable member advances with the closing plate F , the entire member will also advance therewith whenever the 55 slide R^2 moves forward.

The yielding cylinder C is operated by the shaft R^3 by means of two bevel gears S^3 and T^3 . The shaft R^3 takes its movement from the principal shaft Z^2 by means of the pinion U^3 which engages the intermediate pinion B^3 (Fig. 3).

What I claim is:—

1. A cigarette machine including in combination means for continuously feeding a 65 strip of paper and forming it into a continuous tube in line with the strip, and means moving with the tube and cutting off and closing the end of the tube at intervals. 2. Mechanism for closing the end of a cigarette tube including in combination means for feeding the tube forward continuously, and closing means for closing the end of the tube, said closing means being adapted to move forward with the tube during the opera- 70 75

3. Mechanism for closing the end of a cigarette tube including in combination a rod adapted to form a support within the tube against which the end may be closed, and 80 means for moving said rod forward with the tube during the closing operation.

4. A cigarette machine including in combination a carrier composed of a pair of notched end plates J J' , and a second carrier 85 F' adapted to pass between said plates and to receive tubes from said first carrier.

In witness whereof, I have hereunto signed my name in the presence of two subscribing witnesses.

CHARLES ALFRED MARCHAL.

Witnesses:

DENIS MARCHARD,
H. C. COXE.
